[57] **CLAIM**

The ornamental design for a holder for a portable radio telephone, as shown and described.

DESCRIPTION

FIG. 1 is a top front, and left side elevational view of a holder for a portable radio telephone showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a vertical cross-sectional view thereof, taken along line 7—7 of FIG. 2.
